UNITED STATES PATENT OFFICE

THOMAS H. SYMINGTON, OF BALTIMORE, MARYLAND, ASSIGNOR TO T. H. SYMINGTON & SON, INC., OF BALTIMORE, MARYLAND, A CORPORATION OF MARYLAND

ANTIBANKING CAR TRUCK

Application filed August 2, 1927. Serial No. 210,147.

The invention relates to railway trucks and has special reference to that type in which there is lateral motion of the body bolster.

It is well known in the art that it is a common matter to provide side bearings of such construction as to permit lateral motion of the body bolster with respect to the truck side frames when the cars equipped with the trucks pass over curved tracks. It is likewise known that it has been proposed, for instance as set forth in Patent No. 819,480 reissued as No. 13,576 to Westlake to provide a construction wherein or whereby the outer end of the body bolster, that is, the end above the outer rail at a curve, will be caused to move upwardly for obtaining an automatic banking action, the upward movement depending of course upon the specific construction of whatever rollers may be provided as part of the side bearings, the movement occurring as the result of the centrifugal force developed as the car rounds a curve.

In the course of experimentation, I have discovered that owing to the superelevation of the outer rail on a curve substantially twenty-five per cent greater weight is imposed on the inner rail than on the outer. In case of heavy equipment it is apparent that this disproportionate distribution of the load may result disastrously as it is conceivable that the inner rail, being subjected to an excessive strain, may become dislodged or, possibly, damaged. It is also apparent that the truck parts at the inside will very likely be subjected to unusually severe strains and may, under some circumstances, actually fail to withstand them. It is with these facts in view that I have designed the present invention which has for its general object the provision of means which will act automatically upon the development of centrifugal force when a car rounds a curve, to reduce the pressure exerted on the inner rail and correspondingly increase the load on the outer rail, thereby effecting a more uniform distribution of the strains.

The object of the invention, more specifically stated, is to provide a truck having side bearings thereon of such construction that the inner end of the body bolster will be raised

more than the outer end when the car passes over curved track, this raising occurring simultaneously with lateral motion of the body bolster outwardly of the curve.

To the attainment of the foregoing objects and advantages, the invention consists in or comprises the broad features, arrangement and combination to be hereinafter more fully described and claimed, and illustrated in the accompanying drawing which is of a rather diagrammatic nature and in which:

Figure 1 represents an elevation of truck and body bolsters equipped with side bearings of one form embodying the invention,

Figure 2 is a similar view showing a modification, and

Figure 3 is a similar view illustrating yet another modification.

Referring to the drawing, it will be observed that no attempt has been made to illustrate any of the well known structural features of a railway truck as the invention is not intended to be limited in its application to a truck of any particular type. Such being the case it has been deemed sufficient to illustrate only such parts of a truck as will be necessary to give a clear understanding of the general principles involved.

In view of the foregoing explanation, the numerals 1 and 2 designate, respectively, the truck and body bolsters which may be mounted within any suitable side frames, the former being represented as resiliently supported upon springs 3 carried by a sprinck plank 4, and the latter being of course adapted to be mounted beneath a car body in the usual manner. No effort has been made to show any center bearings or other means for guiding the bolsters during relative swivelling movement of the bolsters though it should be understood that such may be provided if found necessary or advisable, in which event they may be of any ordinary or preferred type.

In accordance with the present invention I have disclosed side bearings interposed between the end portions of the truck and body bolsters, it being contemplated that these side bearings be of any desired specific construc-

tion capable of carrying out the object set forth above. The side bearings in the form disclosed in Figure 1 of the drawing comprise bearing members 5 and 6 secured with respect to the truck and body bolsters and having interposed between them a roller 7. The underside of the bearing member 6 may incline downwardly in both directions from its center to provide two inclined bearing surfaces 8 and 9, and the bearing member 5 may have its top surface upwardly inclined from its center toward the center of the truck, to provide an inclined surface 10, the outer portion 11 being horizontal.

As mentioned above, there is no particular restriction in regard to these details and in Figure 2 I have shown exactly the same type of upper bearing member 6, and the same sort of roller 7, the difference being the employment of a somewhat different lower bearing member 12 having its upper surface 13 inclined downwardly and outwardly throughout. Another modification is illustrated in Figure 3 wherein the roller 7 operates between a lower bearing member 5, as in Figure 1, and an upper bearing member 14 having the outer portion of its underside inclined downwardly and outwardly, as at 15 and its inner portion horizontal as shown at 16. Various other combinations of inclined or curved surfaces may readily suggest themselves to one skilled in the art and familiar with railroad practice. For convenience in explanation the ends of the body bolster in each view have applied thereto the reference letters A and B.

In all forms of the invention the operation will be substantially the same and it will be observed that under normal conditions, that is when the car is travelling along straight track, the body and truck bolsters will be in parallel relation. However, assuming that the truck shown in Figure 1 is passing over a track which curves to the right, it will be apparent that the centrifugal force developed will cause the body bolster 2 to move laterally of the truck. When this movement occurs, it will be apparent that the inclined surface 9 at the A end and the inclined surface 8 at the B end will ride on to the rollers 7 and that the roller 7 at the A end will pass along the horizontal surface 11, the roller at the B end riding upwardly onto the inclined surface 10. Clearly, while both ends of the body bolster will be elevated, the end B will be raised more than the A end, thus compensating for the superelevation of the outer rail of the curve. If the truck passes over a track curved to the left, both ends of the body bolster will be elevated but the A end will be raised higher than the B end.

In the case of the truck shown in Figure 2, it will be apparent that if it passes over a track curved to the right, the roller 7 at the A end will roll down the inclined surface 13

while the roller at the B end will roll upwardly, thus resulting in a greater raising of the B end than the A end. The reverse is true in case the truck passes over track curved to the left, the A end then rising more than the B end.

In the form disclosed in Figure 3, it will be apparent that when the body bolster 2 moves to the left, as the result of passing over track curved to the right, the roller at the A end will engage between the two horizontal surfaces 11 and 16 and will not rise at all whereas the roller at the B end will ride upwardly along the inclined surface 10 and beneath the horizontal surface 16, thus accomplishing the same elevation of the B end. When passing over track curved in the opposite direction the action will be reversed.

In all forms of the invention it will be apparent that the action is the same and it is conceivable that other specifically shaped surfaces may be applied to equal advantage and that, if desired, specially constructed rollers might be provided either in conjunction with horizontal bearing plates or certain appropriately curved or inclined ones. In fact, I reserve the right to make all such changes in the detailed arrangement and structural features as will fall within the spirit of the invention and not constitute a departure from the scope of the claims hereunto appended.

Having thus described the invention, I claim:

1. In a railway truck, the combination of a truck bolster, a body bolster capable of lateral motion with respect to the truck, and roller bearing means for raising the inner end of the body bolster to a greater height than the outer end thereof with respect to the truck bolster upon the occurrence of lateral motion.

2. In a railway truck, the combination of a truck bolster, a body bolster capable of lateral motion with respect to the truck, and roller bearing means interposed between the end portions of the bolsters for raising the inner end of the body bolster with respect to the outer end thereof with respect to the truck bolster upon the occurrence of lateral motion.

3. In a railway truck, the combination of a truck bolster, a body bolster mounted for lateral motion with respect to the truck, lateral motion rollers interposed between the bolsters, and means cooperating with the rollers for raising the inner end of the body bolster with respect to the outer end upon the occurrence of lateral motion.

4. In a railway truck, the combination of truck and body bolsters, the latter being mounted for lateral motion with respect to the truck, and cam means interposed between the end portions of the bolsters for raising the inner end of the body bolster with respect to

the outer end upon the occurrence of lateral motion.

5. In a railway truck, the combination of a truck bolster, a body bolster mounted for lateral motion with respect to the truck, and roller bearing means interposed between the end portions of the bolsters whereby when the truck passes over curved track and lateral motion of the body bolster occurs the 10 end of the body bolster above the inner rail of the curve will be raised with respect to the other end.

6. In a railway truck, the combination of a truck bolster, a body bolster mounted for 15 lateral motion with respect to the truck, and roller bearing means interposed between the end portions of the bolsters whereby when the truck passes over curved track and lateral motion of the body bolster occurs the end 20 of the body bolster above the inner rail of the curve will be raised with respect to the truck bolster more than the end of the body bolster above the outer rail of the curve.

In testimony whereof I affix my signature.

25 THOMAS H. SYMINGTON.
